[57] CLAIM

The ornamental design for orthopedic splint for animal leg, as shown and described.

DESCRIPTION

FIG. 1 is a top and side perspective view of an orthopedic splint for animal leg, showing our new design;

FIG. 2 is an end view thereof, the opposite end being identical;

FIG. 3 is a top plan view thereof;

FIG. 4 is a side elevational view thereof, the opposite side being identical;

FIG. 5 is a bottom plan view thereof; and,

FIG. 6 is a another perspective view showing the orthopedic splint applied to a hind leg of a quadruped animal such as a dog or a cat.

The broken lines in FIG. 6 are for purposes of illustration only and form no part of the claimed design.
